PLAYGROUND BACKHOE APPARATUS

Robert S. Wormser and Ronald L. Ewers, Hillsdale,
Mich., assignors to Game Time, Inc., Hillsdale, Mich.

Filed Mar. 3, 1972, Ser. No. 231,792

Term of patent 14 years

Int. Cl. D21—03

U.S. Cl. D34—15 T

FIG. 2

FIG. 3

FIG. 5

FIG. 4

FIG. 6

FIG. 1 is a perspective view of a playground backhoe apparatus showing our new design;

FIG. 2 is a reduced side elevational view thereof;

FIG. 3 is a plan view thereof;

FIG. 4 is a perspective view thereof when employed without the base;

FIG. 5 is a side elevational view of FIG. 4; and

FIG. 6 is a plan view of FIG. 4.

We claim:

The ornamental design for playground backhoe apparatus, substantially as shown and described.
